Fig 5

Fig 6

FIG. 1 is a side elevational view of a pocket lighter, or similar article, showing my new design with the hinged combined operating lever and cover in closed position;

FIG. 2 is an end elevational view thereof, in which the hinge is shown;

FIG. 3 is a side elevational view;

FIG. 4 is an end elevational view, in which the knurled portion of the hinged combined operating lever and cover is shown;

FIG. 5 is a top plan view;

FIG. 6 is a bottom plan view;

FIG. 7 is a large scale perspective view showing the pocket lighter, or similar article, with the hinged combined operating lever and cover in open position wherein the lighter is actuated;

FIG. 8 is a perspective view, similar to FIG. 7, showing the hinged combined operating lever and cover in closed position (as in FIGS. 1-5) wherein the lighter is inactivated; and

FIG. 9 is a perspective view, showing predominantly the surfaces of FIGS. 1 and 2.

I claim:

The ornamental design for a pocket lighter or similar article, substantially as shown and described.
